[57] CLAIM

The ornamental design for a data entry and display terminal, as shown and described.

DESCRIPTION

FIG. 1 is a right, top, rear perspective view of the data entry and display terminal showing our new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a right, top, rear perspective view of a second embodiment of our new design, the front edge being identical to the rear edge and the sides and bottom being identical to those of the first embodiment as shown in FIGS. 4, 5, and 7.
